UNITED STATES PATENT OFFICE.

MAX POETZSCH, OF CLIFTON, NEW JERSEY.

AUTOMATIC FEEDER.

1,325,373.

Specification of Letters Patent. Patented Dec. 16, 1919.

Application filed March 21, 1919. Serial No. 284,006.

To all whom it may concern:

Be it known that I, MAX POETZSCH, a citizen of the United States, and a resident of Clifton, in the county of Passaic and State 5 of New Jersey, have invented a new and Improved Automatic Feeder, of which the following is a full, clear, and exact description.

This invention relates to feeding devices, 10 and particularly to an automatic feeder for various kinds of machines, as for instance drying, tentering, selvage neutralizing and carbonizing machines.

The object of the invention is to provide 15 an automatic feed which will cause an automatic adjustment of the various parts whereby the cloth as it enters the machine will properly engage the pins, clasps, or other cloth engaging members so that the 20 cloth will be stretched, dried, and otherwise operated upon without any action on the part of an operator.

Another object of the invention is to provide 25 an automatic feed which will automatically shift the cloth engaging members as described so as to properly engage the cloth and cause the same to fit into the machine in a proper manner and will sound an alarm in case the cloth gets beyond the control of the mechanism.

A still further object of the invention is 30 to provide a feeding device which is readily applicable to various machines now on the market and which may be also adjusted for various widths of cloth.

In the accompanying drawings:

Figure 1 is a fragmentary side view of 35 the front part of a tentering machine showing an embodiment of the invention applied thereto.

Fig. 2 is a fragmentary front view of the structure shown in Fig. 1, with the invention shown in operative position thereon.

Fig. 3 is an enlarged fragmentary sectional view through Fig. 2 on line 3—3.

Referring to the accompanying drawings by numerals, 1 indicates the frame of a tentering machine, which machine may be of any desired type and supplied with the usual 50 chain 2 having needles, pins or clamps 3 for engaging the edge of the cloth so as to move the cloth through the machine and stretch it at the same time. As the tentering machine is old and well known no particular description thereof will be provided, especially as the invention resides merely in

the automatic feed therefor, which will cause the cloth to be properly fed to the needles 3 without the use of an operator. The members 3 on the drawing have been 60 shown as needles or pins, but it will be evident that clasps, hooks or any other desired form of cloth engaging members may be used without departing from the spirit of the invention.

In producing a structure of this kind a reciprocating rod 4 is provided as shown in Fig. 2, guided by any suitable guide and continually reciprocated by a link 5 eccentrically mounted on the rotating disk 6, 70 whereby as said disk rotates during the operation of the machine the back and forth movement of rod 4 will be maintained. This rod may freely move back and forth, but cannot rotate. Adjacent the opposite ends 75 of this rod, sets of teeth 7 and 8 are provided, the teeth at each end facing in opposite directions so as to engage at the proper time a locking plate 9, which plate is preferably a disk except for the cutaway portion 10, whereby the bar may slide sufficiently near to be engaged by the projections 11 and 12 when the disk is turned. It will be noted from Fig. 2 that the teeth 7 and 80 8 on bar 4 are arranged so that the teeth 85 7 at the right end will face to the right and at the left will face to the left, while the teeth 8 at the right end will face to the left and the teeth 8 at the left will face to the right. This arrangement is provided so that 90 when the disk 9 engages the teeth 8 from either end of bar 4 the disk and the parts connected therewith will be moved inwardly toward the center, while if the disk 9 engages the teeth 7 on either end of the bar 95 all of the parts will be moved outwardly or away from the center of the machine.

The disk 9 is loosely mounted on a shaft 13 which is connected with the side walls of a housing 14, which housing is rigidly secured in any desired manner to the substantially U-shaped bar 15, as for instance by screws 16. Bar 15 may be supported in any desired manner on the frame 1, and in such manner as to freely reciprocate within 105 short limits. The casing 14 is provided with an opening or slot 17 through which the segmental shaped plate 18 extends, said plate having teeth 19 on the outer end, while the inner end is loosely mounted on 110 the shaft 13. In order that a movement of the plate 18 may move the disk 9, plate 18

is provided with a slot 20 through which a pin 21 extends, said pin being connected with the plate 22 formed integral with disk 9. The disk 9 would ordinarily move down 5 pivotally under the action of gravity until the projection 12 should engage the tooth 8 but for the action of the cloth entering the machine. The cloth in passing over the teeth 19 of bars 18 and 22 engage the same 10 somewhat, namely sufficiently to hold the projections 11 and 12 out of engagement with bar 4. The selvage of the cloth has a less tension than the body of the cloth so that when the cloth is being properly fed 15 into the machine the selvage scapes over the teeth 19 and merely holds the parts in position as shown in Fig. 3, but in case the cloth should move too far over on to the teeth the body of the cloth would engage the teeth 20 and being tighter would swing the plates, including the disk 9 upwardly until the projection 11 was in engagement with one of the teeth 7. This would cause a lateral movement in a direction away from the 25 center of the cloth. This lateral movement is communicated, of course, through the frame 14 to the U-shaped bar 15 and from thence through the arm 41 to member 39 and also to the yoke 42 which fits into the 30 groove in the hub of wheel 40' whereupon the sprocket wheel 40' and the chain 2 carried thereby are moved to the edge of the cloth so that they will engage only the selvage. The same operation takes place on 35 both sides of the machine so that the chains 2 are caused to follow the cloth in such a manner that the pins 3 will engage the selvage only.

In operation, the cloth is arranged as 40 shown in dotted lines in Fig. 2 with the selvage edges overlapping the plates 18 and 22 on each side of the machine so that as the cloth passes into the machine it will move over the teeth 19 and hold the plates 45 in a neutral position as shown in Fig. 3. If, however, the cloth should move to one side until the body of the cloth was over the plates 18 and 22 the tension of the cloth would cause an engagement with the teeth 50 19 so that the plates 18 and 22 would swing upwardly and rotate the disk 9 a sufficient distance to cause the extension 11 to engage one of the teeth 7 on bar 4. When this takes place the bar or rod 4 will pull the plate 55 9 and associate parts including arm 41 so that the sprocket wheel 40' and the chain 2 carried thereby will be moved to a position beneath the selvage, the movement being in a direction away from the center of the machine. The pulling action provided by this 60 mechanism will be repeated until the machine has been moved to a proper position for the pins or needles 3 to engage the selvage. This occurs on either side of the machine as may be necessary. In case the cloth 65

moves toward the center of the machine and consequently moves entirely off of the teeth 19 plates 18 and 22 will drop downwardly and thereby rotate the disk 9 so that the projection 12 will engage one of the teeth 70 8. As bar 4 is continuously moving this will cause bar 18 to move plate 9 and all parts associated therewith including arm 41 and sprocket wheel 40', the movement being toward the center of the machine. This 75 movement is repeated until the needles 3 are brought beneath the selvage.

As the cloth being fed into the machine is arranged in a pile or on a roll at a given point adjacent the machine the movement 80 of the cloth will naturally be very small and consequently the adjustment of the machine will be but small, but in any event the needles 3 will follow the selvage in either direction and thereby not in any way damage the cloth, while at the same time automatically acting to engage the cloth at the right point. It is, of course, to be understood that after the selvage has been hinged on the needles 3, or otherwise engaged by 85 the members carried by the chains 2 it will move into the machine and become stretched in the usual manner as determined by the way the machine is set.

As the cloth is fed into the machine it 95 passes through suitable guiding shoes 23 and 24 pivotally mounted on arms 25 and 26, which arms are rigidly secured to sleeves 27 and 28. These sleeves and associate parts are identical, so that the description of one 100 will apply to both. A post 29, for instance, is connected with the sleeve 28, said post having an arm 30 pivotally connected therewith, said arm having a pivotal bar 31 as shown in Fig. 1, which bar in turn carries a roller 32. Adjustable contact members 33 and 34 are connected to the bar 31, and suitable electrical connections are connected with these contact members, said connections being also connected with a sounding device, whereby when these contact members are brought together the current will be closed for operating the sounding device, which may be any desired kind, as for instance an ordinary electric bell. These contacts are held apart by the weight of the roller 32. In case the cloth should move over to a position beneath the roller 32 sufficiently to cause the contacts to be engaged, whereupon the alarm will be sounded and an attendant may come and re-adjust the machine if same is desirable, though ordinarily the bar 4, plate 18 and associate parts will re-adjust the machine automatically.

As another safety appliance, a second alarm is connected to the contact points 35 and 36. Contact 36 is connected with a stationary post 37, which may be supported in any suitable manner, as for instance by a bar 120 125

38 secured to the supporting frame 39. This frame in turn is supported by suitable anti-friction means and a transverse bar 40. The movable contact 35 is connected to the 5 swinging feeler bar 35', which is pivotally mounted on the post 37, and normally rests on the cloth roll immediately above the needles so that when the cloth moves off of the needles feeler 35' will swing downwardly 10 under the action of gravity and move contact 35 into engagement with contact 36 for sounding an alarm.

When any operator in the vicinity hears either of the alarms above mentioned they 15 are supposed to look the feeding apparatus over and re-adjust the cloth or the machine if the same is necessary. By the mechanism just described alarms are sounded when the cloth moves laterally in one direction or laterally in another direction. In addition 20 mechanism has been provided for actually pulling chains adjacent either edge, whereby the chain is automatically maintained in the proper feeding position for the needles 25 3 to engage the selvage as the cloth enters the tentering machine. Heretofore one, two or more operators were necessary to feed the cloth into the tentering machine in order that the needles would engage the selvage 30 properly, so that the cloth could not only be dried, but stretched during the drying action, and thereby caused to assume the proper shape and to present the proper appearance. It will be noted that when a strip 35 of cloth is passed into the machine properly none of the automatic mechanism is operated except rod or bar 4, which continually reciprocates at all times. If the cloth moves to either side one of the plates 18 or 22 begins 40 to pull the chain back and if the movement is appreciable one of the alarms will be sounded. The parts are set, preferably, so as to give the automatic part of the mechanism a chance to adjust the chain, but the 45 signals are arranged to sound before the cloth has moved to one side a sufficient distance to do any injury.

Heretofore usually two persons were used to feed cloth into one tentering machine, 50 but with this automatic structure for shifting the chain back and forth one attendant may cause the feeding mechanism to properly operate in a number of machines, or rather oversee the feeding of a number 55 of machines. It is, of course, evident that the feeding arrangement may be adjusted back and forth to take care of different widths of cloth, which is also true of the tentering machine forming no part of the 60 present invention.

What I claim is:

1. An automatic feeder for drying machines, tentering machines and the like comprising a constantly reciprocating power rod, an arm for shifting the mechanism of 65

said machines, means operated by the cloth as it enters said machines, said last mentioned means when moved a predetermined distance by the cloth acting as a connecting member between said arm and said power 70 rod, a signal member, and means for causing the operation of said signal member when the cloth moves a predetermined distance in either direction.

2. An automatic feeding device of the 75 character described comprising means set in motion by the cloth for shifting the chains of the machine to which the feeder is attached, a pair of circuit closing means operated by the cloth when the cloth moves laterally for too great a distance in either direction, a second pair of circuit closing means operated when either edge of the cloth is moved toward the center a predetermined distance, and a signal device connected 80 with each of said circuit closing means.

3. An automatic feeding device of the character described comprising means for shifting the mechanism of the machine to 90 which the feeder is attached for causing the same to follow the cloth, a roller arranged adjacent each edge of said cloth and out of contact therewith, a pivotally mounted arm for supporting each of said rollers, an electrical contact connected with said pivotally mounted arm, a fixed contact arranged adjacent said first mentioned contact, pivotally mounted arms holding said rollers in such a position as to be elevated by the cloth when 95 moved laterally, said elevation causing said contacts to engage, and an electrically operated signal connected with said contacts whereby when the cloth moves in one direction for too great a distance a signal will be 100 sounded in addition to the shifting action of the feeder.

4. An automatic feeder of the character described comprising means for shifting the mechanism of the machine to which the device is secured, an alarm device for indicating when either edge of the cloth moves for 110 too great a distance toward the center, said alarm device being arranged with duplicate contact closing means on each side of the 115 machine, each of said contact devices comprising a supporting member having an electrical contact, a pivotally mounted arm having an electrical contact, said pivotally mounted arm being arranged substantially 120 in line with and above the cloth receiving means of the machine to which the feeder is attached so that when either edge of the cloth moves transversely inwardly a predetermined extent said lever will move downwardly under the action of gravity and close 125 said contacts.

5. An automatic feeder of the character described comprising a reciprocating power member reciprocating transversely of the 130

cloth, but in a plane substantially parallel with the surface thereof, a cloth clasping means on each side of the machine adapted to be brought into engagement with said reciprocating bar for shifting the mechanism of the machine to which the feeder is secured so as to receive the cloth in proper position, the cloth clasping means being capable of resisting the friction of the cloth as the same passes thereover when moved in a correct path, but adapted to be moved by the cloth when engaged by the body of the cloth, said movement of the clasp caused by the cloth resulting in the clasp engaging said bar whereby motion is transmitted to the clasp and associate parts for shifting the mechanism of said machine.

6. An automatic feeder of the character described comprising a toothed reciprocating member with two sets of teeth on each end, the sets of teeth on each end facing in opposite directions, the cloth feeding into the machine being adapted to be fed over the central part of said member, a sliding

member arranged at each end of the toothed member, a pivotally mounted catch carried by each of said sliding members formed with opposite projections adapted to be brought into engagement with the respective teeth on said toothed member, said catches being arranged to engage the cloth when the same is moved too far in one direction so that one of the projections of the respective catches will engage one set of teeth and when the cloth has moved too far in the opposite direction the catches will be released so that the opposite projection thereof will engage the opposite set of teeth under the action of gravity whereby as the toothed member reciprocates and engages said projection the respective sliding members will be moved laterally of the cloth receiving members of the machine to which the device is secured, with the respective slides so as to cause the cloth receiving members to move over to the selvage.

MAX POETZSCH.
